UNITED STATES PATENT OFFICE.

HARRY D. FORSE, OF ANDERSON, INDIANA.

WINDOW-SHADE.

1,280,699.

Specification of Letters Patent.

Patented Oct. 8, 1918.

Application filed January 3, 1918. Serial No. 210,136.

To all whom it may concern:

Be it known that I, HARRY D. FORSE, a citizen of the United States, and a resident of Anderson, county of Madison, and State 5 of Indiana, have invented a certain new and useful Window-Shade; and I do hereby declare that the following is a full, clear, and exact description thereof, reference being had to the accompanying drawings, in 10 which like letters refer to like parts.

This invention relates to improvements in shade hangers and particularly to that class wherein the shade is suspended and operated by means of a cord and pulleys. One feature 15 of the invention is the manner of attaching the cord employed for suspending the shade and the roller construction attached to the shade. A further feature of the invention is to so attach the cord to the roller upon the 20 shade, that the upper bar of the shade will extend slightly rearwardly at its upper edge when the weight of the curtain is directed upon the part of the cord sustaining the weight of the shade, and a further feature 25 of the invention is to so construct that portion of the roller supporting frame on the shade to which the cord is attached that when a downward pull is given to the cord to raise the shade to a folded position, it will cause 30 the upper bar of the shade to assume an upright position and extend in direct alignment with the remainder of the shade, whereby the parts of the shade may be folded together without undue friction or 35 the catching of one part of the shade upon another part.

The full nature of this invention will be understood from the accompanying drawings and the following description and 40 claims:

Figure 1 is an elevation of a window frame showing the shade suspended therefrom and in partially folded position. Fig. 45 2 is a sectional view thereof as seen on line 2-2 of Fig. 1. Fig. 3 is an end elevation of the roller used in connection with the shade. Fig. 4 is a front elevation thereof and Fig. 5 shows a different form of roller construction and manner of attaching the 50 end of the supporting cord thereto.

Referring to the drawings in which similar reference numerals designate corresponding parts throughout the several views, 1 indicates a window frame which may be of any 55 preferred construction and 2 indicates a shade, preferably of fabric, which is provided at its upper and lower ends and sub-

stantially at its longitudinal center with bars 3, 4 and 5 respectively, said bars being secured in loops at the ends and center portion. The shade 2 is supported by a cord 6 which passes over a pulley or roller 7 attached to the upper bar 8 of the frame 1, said roller being of the usual stepped variety so that when the cord is in one position on 60 the roller, it will bind on parts of the roller and prevent the cord from passing over the roller and when in another position will readily pass over the roller and permit the curtain to bodily descend.

One end of the cord 6 is attached to a bracket 9 on the roller carrying frame 10, said bracket being preferably angular and the horizontal portion 11 thereof provided with a recess 12 for the reception of the 75 cord 6, the vertical portion of the bracket 11 having arms 13 in the form of hooks around which the cord passes. The cord is attached to the bracket 9, by forming a knot 14 on the loose end of the cord which is placed above the horizontal portion 11, the 80 cord 6 being then brought down through the recess 12 and extended below the arms 13 and then extended upwardly and again through the recess 12, said recess being provided with a registering way 15 through 85 which the parts of the cord may be introduced into the recess.

Instead of forming a knot 14 at the end of the cord, any suitable form of button or 90 enlargement may be provided for preventing the end from pulling out of the recess.

The arms 13 extend forwardly a less distance than the horizontal portion 11 of the bracket so that when the weight of the shade 95 is directed against the cord the upper bar 3 to which the frame 10 is attached, will be directed at an inward inclination toward the frame as best shown in Fig. 2, the cord causing a slight rearward pressure on the 100 upper portion of the bracket.

In order to raise and fold the lower portion of the shade without moving the shade bodily, the cord after passing over the bracket 9 and the roller 7, is introduced over a roller 105 16 carried by the frame 10 and through eyes 17 and 18 on the bars 5 and 4 respectively, the end of the cord being attached to the eye 18 in any suitable manner. The roller 16 is constructed similar to the roller 7 so 110 that when the cord is at one point on the roller it will freely pass over the roller, but when moved to other parts of the roller it will bind against the frame carrying the

roller and prevent further movement of the cord.

In Fig. 5 of the drawings a slightly modified form of frame 10^a is provided, said frame having a horizontal extension 19 which projects forwardly of the roller 20 carried by the frame 10^a, said horizontal extension having openings 21 adjacent its ends for the passage of the cord 6^a and in this manner of attaching the cord to the frame, the free end of the cord is first passed downwardly through one of the openings 21, then across the top of the horizontal extension 19, thence upwardly through the other opening 21 and the free end then tied or otherwise secured to the remaining portion of the cord at a point above and at the longitudinal center of the frame 10^a, and as the openings 21 are positioned forwardly of the back face of the frame 10^a said frame and the bar attached thereto will likewise be tilted rearwardly when the weight of the curtain is suspended on that portion of the cord between the frame 10^a and the upper roller 7.

In operation, when it is desired to admit light into the building through the lower portion of the window, a downward pull is given to that portion of the cord 6 passing over the roller 16 so as to move the bar 4 and the part of the curtain attached thereto upwardly, such downward pull causing the bar 3 to assume a vertical position and extend directly in line with the shade depending therefrom, thereby permitting the lower portion of the folding portion of the shade to pass upwardly over the face of the remaining portion of the shade without catching on any part thereof or without undue friction, so that said shade will be smoothly and uniformly folded.

When the lower part 4 has been moved upwardly and into engagement with the middle bar 5, said bar 5 and the portion of the curtain above the same will also be folded in the same manner as the part of the shade is folded below the middle bar, thus permitting the shade to be assembled or brought together in the same manner, so as to occupy a minimum amount of space. As soon as the pull on the cord 6 is released the bar 3 will instantly return to its inclined position and will remain in said position until such time as the cord is again given a downward pull. If it is desired to lower the shade bodily a pull on that portion of the cord extending over the roller 7 is made which will move the cord to a portion of the roller 7 where the cord will readily travel over the roller and permit the shade to descend. As soon as the shade has been lowered or raised a proper degree, the cord is again caused to travel over the enlarged

portion of the roller 7 so as to bind the cord against the parts of the frame carrying the roller 7 and thus stop a further descent of the shade.

The invention claimed is:—

1. In a shade hanger, the combination with a fixed pulley, a shade structure, bars on said shade structure, a pulley construction on the bar at the upper end of the shade, a cord for operating said shade, a bracket comprising a vertical portion integral with the rear edge of the pulley construction and a horizontal section integral with the upper end of the vertical portion and extending forwardly over the pulley construction, and means to attach the cord to the forwardly extending portion of the bracket in such a manner as to cause the upper bar to be rearwardly inclined when the weight of the shade is suspended from the cord and to assume an upright position when a pull is given parts of the cord. 85

2. In a shade hanger, the combination with a stationary pulley and a cord passing thereover, of a shade, a bar at the upper end of said shade, a pulley carrying frame attached to said bar, an upwardly and forwardly extending bracket on said frame, and means to attach the cord to the forwardly extending portion of said bracket whereby said bracket and bar will be slightly rearwardly inclined when the shade is suspended from the cord and brought to an upright position when a downward pull is given to that portion of the cord passing through the frame attached to said bar. 95

3. In a window shade structure, the combination with a stationary pulley and a cord passing thereover, of a shade, a bar at each end of the shade and at the longitudinal center thereof, a frame carried by one of said bars, a bracket carried by the frame comprising a vertical and horizontal section, said horizontal section having a recess for the reception of said cord, and arms on the vertical portion of the bracket around which the cord extends. 100

4. The combination with a shade and a bar at the upper end of the shade, of a pulley construction attached to said bar, a cord for coöperation with said pulley construction, and means to attach the cord to said pulley construction forwardly of the rear face of the pulley construction whereby the pulley construction and parts attached thereto will be normally rearwardly inclined. 115

In witness whereof, I have hereunto affixed my signature in the presence of the witnesses herein named.

HARRY D. FORSE.
